Hal Charles Greene INVENTOR.

UNITED STATES PATENT OFFICE

1,937,954

GARMENT DISPLAYING DEVICE

Hal Charles Greene, Louisville, Ky.

Application May 3, 1933. Serial No. 669,122

1 Claim. (Cl. 223—18.1)

My invention relates to fashion forms and plaques designed to display such wearing apparel as women's dresses and cloaks; and the objects of my present invention are: First, to provide an oblong plaque adapted to be adjustably mounted on a garment-displaying standard having shoulder drapery bars across its upper end; second, to design this fashion plaque with outlines, longitudinal furrows and curves so that, a perfect feminine contour is imparted to the garment properly draped thereon; third, to devise, in combination with said draping plaque, a system of unique garment clamps spring-pressed and provided with long shanks bowing outwardly and adapted to be operated with the fingers while the clamps are under the garment draped over the plaque. Another object of my invention is to design a garment-displaying device that will be low-priced in production as well as efficient in service, and so thin from front to back that it requires much less space than ordinary display forms in show windows where space is an important consideration. Another object is to produce a garment-displaying device that can be artistically draped with any one of various sizes of garments without the use of pins by a draper not wholly proficient in the art.

All of these objects and others to which I shall hereinafter refer, are attained in my present invention; and my new and useful garment-displaying device illustrated in the accompanying drawing which forms a part of this specification, is a practical apparatus embodying the aforesaid novel means and other new and useful details of construction, arrangement and combination of parts; all of which, together with their functions, will be described in detail with reference to said drawing and will be definitely pointed out in the claim that follows the description, that any one skilled in the art to which my invention appertains, may be enabled to make and use the device.

In said drawing:

Figure I is a front elevation of my garment-displaying device as it would appear normally mounted on a display standard provided with usual shoulder-bars at the upper end and properly draped with a feminine dress.

Fig. II is a front elevation of my garment-displaying device normally mounted on an ordinary garment-displaying standard provided with the usual shoulder-bars at the upper end, showing my garment-displaying plaque clamped on the standard in its normal functional position, with the garment removed.

Fig. III is a back elevation of my garment-dis-

playing device and a fragment of the rod of the standard, showing the thumb-screw clamp that fastens the device at a predetermined height on the standard and the spring-pressed garment-clamps designed to hold the parts of the garment in their proper positions for artistic drapery. In this view is shown, also, a fragment of a garment draped around the edge of the plaque and properly folded and held in place by one of the garment clamps.

Figs. IV and V, respectively show a side elevation and an edge view of the thumb-screw clamp that fastens the display plaque onto the display standard at any desirable height; the back side of said clamp being shown fastened to the back part of said plaque.

Fig. VI is a side elevation in detail of a fragment of the spring-pressed garment clamp and the housing of its actuating spring; and Fig. VII is a detail view of the torsion spring which is adapted to exert a continuous pressure upon the garment clamp to hold the folds of the displayed garment in their normal positions.

Fig. VIII is a cross section of the garment-displaying device disclosing the longitudinal furrows and curves, cut along the line C D of Fig. III and showing an edge view in elevation of the clamp attached to the back of the plaque and holding it to the rod of the display standard.

Fig. IX is a cross section, on the line A B of Fig. III, showing a sectional view, through the waist clamps, of the garment-displaying device and the cross lines of the garment properly draped thereon, with its draping folds showing under the garment clamps.

Figs. X and XI are detail views respectively of a side elevation and a plan view of the spring-pressed garment clamp, showing the outward bend of the shank and the felt lining on the bottom of the clamp.

The drawing herein shown, clearly illustrates the elements of this invention of mine; but it should be understood, of course, that various modifications to facilitate economical fabrication or otherwise, may be made in the dimensions and particular details of the construction herein illustrated, without departing from the spirit and scope of my invention as set out in the specification and the appended claim. With the aforesaid objects in view, therefore, I will now describe my invention in detail, pointing out the new and useful features and explaining the uses and operations of the individual parts and combinations thereof as illustrated in the above drawing in

which similar characters refer to similar parts throughout the several views.

The oblong drapery plaque 1 is constructed with longitudinal furrows 1a, 1a, along its medial portion, which is somewhat depressed below the rounded front sides 1b, 1b which are convex following the natural curves of the human form, while the edges 1c, 1c, thereof are rolled backward, to afford the appearance of rotundity to 10 the front of the garment draped thereon. The display plaque 1 is held in its functional position by means of clamp 6, 6' on the rod 2 of the display standard whose pedestal 4 is broad and heavy enough to hold the draped garment-displaying device in equilibrium for its predetermined purpose of display.

In draping a garment over my display plaque, the usual shoulder-bars 3, 3, are essential for the purpose of supporting the weight of the garment and of giving natural form to the outline of the shoulders of the garment, as disclosed in Fig. I.

In the upper end of the plaque 1, I have designed a broad recess or bay extending nearly 25 across the upper end of the plaque and low enough to be invisible when normally draped with a woman's dress of average low-neck design.

The rounded upper ends 1d, 1d of the extensions of the curved sides 1b, 1b, towards the 30 shoulder-bars, are adapted to fill out and give natural outlines to this part of the garment displayed on my drapery plaque.

To mount my display plaque on the ordinary garment displaying standard, we first unscrew 35 the thumb-screws 6a, 6a far enough to release, at least, one end of the outside part 6' of clamp 6, 6', so that it can be fitted over the rod 2 of the display standard and then screwed back again into its functional position against the enclosed 40 rod tightly enough to anchor the display plaque on the rod at a desirable height, according to the length of the garment to be displayed, as shown in Fig. II, the display plaque 1 and the shoulder bars 3, 3, being adjusted in the same plane. I have designed the clamp, 6, 6', so that 45 it can be thus securely anchored in its functional place on a square or a flat rod, as well as on a round rod, of a display standard.

The garment to be displayed, we next place on 50 over the standard upon which are mounted the shoulder-bars, 3, 3, and the display plaque 1, first fitting the shoulder-bars, 3, 3, artistically into the shoulders of the garment and allowing the garment to hang loosely thereon down to its full 55 length. And we then proceed to fit the front of the garment smoothly and evenly over the convex front of the display plaque, as shown in Figs. I and IX, carrying the slack part of the garment back into the long concavities of the back of the plaque in smooth and even folds, 5a, 5a, dexterously folded under the garment clamp-plates, 7b, 7b, as shown in Figs. III and IX. This operation is performed by holding the garment fold 5a in one hand and pushing it under the garment clamp-plate 7b while grasping the long, bowed clamp-shank 7 with the other hand in lifting the clamp-plate. This operation can be easily per-

formed, even though the garment-clamps mounted on the back of the display plaque, are always inside of the garment to be draped over the plaque; for the clamp-shank has been adapted for this kind of service; being long and adequately bowed out so that it can readily be grasped under the material of the garment. It is now clearly seen that in this drapery process with my display-plaque no pins or other accessories of drapery are needed. And no matter how delicate or sheer the material of the garment may be, there is no danger of its being cut or chafed by these garment clamps, since the clamp-plates, 7b, 7b, are provided with soft felt linings, 7c, 7c, and broad spaces under the clamp are securely 90 covered with soft felt pads 8, 8, securely fastened to the plaque. And when my garment-displaying device has been properly arranged and artistically draped with a woman's dress, it will present the appearance as illustrated in Figure I of the drawing and be ready for display. This result should be ordinarily accomplished by the average window-dresser in less than two minutes, thus saving much valuable time necessarily involved in such work heretofore. 100

And, now, having described the various features of my invention, the detail construction, arrangement, purposes and methods of operation, I wish to explain that those features and combinations of my invention that I consider new and useful and representative of utility and efficiency, on which I desire Letters Patent granted to me, I have hereinbelow set forth and specifically described in the following appended claim:—

I am aware that prior to my invention various 110 kinds of garment-displaying devices, such as full human forms and flat board figures, have been made and extensively used, with and without standards, therefore, I do not claim broadly any features of such devices; but— 115

I claim: 120
 A garment-displaying device of the character of the one described, comprising an oblong display plaque having longitudinal furrows and convex, curved sides extending the entire length 125 thereof adapted to be readily mounted at any desirable height on the rod of an ordinary display standard having thereon the usual shoulder-bars adapted for the display of garments; spring-pressed garment-clamps fastened on the back 130 sides of said display plaque provided with long, outwardly bowed shanks and felt-lined clamp-plates, adapted to clamp and hold the slack folds of any garment draped on said garment-displaying device; a broad recess in the upper end of said 135 plaque adapted to render the plaque invisible when draped with a cloak or dress of the low-neck design; side edges on said display plaque rolled backward and adapted to prevent the sharp-edge appearance on the sides of the garment draped 140 thereon; the garment-displaying device when properly draped being adapted to take very little floor space in a show window, and further adapted to consume very little time in artistically draping the various garments thereon, substantially as described.

HAL CHARLES GREENE.
